Fraunzef and Richards,
ATTORNEYS.

UNITED STATES PATENT OFFICE.

SIDNEY MITCHELL, OF NEW YORK, N. Y.

PULP BEATER.

Application filed April 4, 1925. Serial No. 20,712.

This invention relates, generally, to improvements in pulp beating machines commonly employed in the paper manufacturing industry; and the invention has reference, more particularly, to an improved construction of beater adapted to rapidly break down and tease out the fibres of raw-stock, such as rag, wood, straw, etc., but which is especially effective in the pulping of straw and similar tough raw stocks.

The invention has for its principal object to provide a novel construction of pulp beating machine which is more efficient and rapid in its circulation and treatment of the raw stock; which is especially adapted to treat tough fibred stock without likelihood of clogging; and which by reason of its rapid action is adapted to save both time and power in carrying out the pulping operation. With such objects in view, this invention provides a novel construction of pulp beating machine equipped with a plurality of breaker or beater rolls set at different points in, what may be termed, a continuous "circular run" trough or tub; said beater rolls comprise, essentially, a primary roll set in one relation to the bed-plate with which it cooperates, and a secondary roll set in another relation to the bed-plate with which it cooperates; the primary roll being adapted to initially break up the raw stock and the secondary roll being adapted to tease out the fibres of the initially broken down raw stock.

The invention has for a further object to provide means for assisting the flow of stock under treatment over the back-falls which are adjacent to the respective beater rolls.

Other objects of this invention, not at this time more particularly enumerated, will be clearly understood from the following detailed description of the same.

With the various objects of this invention in view, the same consists, primarily, in the novel construction of pulp beater hereinafter set forth; and, the invention consists, furthermore, in the novel arrangements and combinations of the various devices and parts, as well as in the details of the construction of said parts, all of which will be hereinafter more fully described in the following specification, and then finally embodied in the appended claims.

The invention is clearly illustrated in the accompanying drawings, in which:--

Figure 1 is a plan view of the novel pulp beater made according to and embodying the principles of this invention; Figure 2 is a longitudinal vertical section, taken on line 2--2 in Figure 1; Figure 3 is a part vertical longitudinal section and part side elevation, taken on line 3--3 in Figure 1; Figure 4 is a fragmentary perspective view of a portion of the primary beater roll and its fly-bars; and Figure 5 is a similar fragmentary perspective view of a portion of the secondary beater roll and its fly-bars.

Similar characters of reference are employed in all of the hereinabove described views, to indicate corresponding parts.

Referring now to said drawings, the reference character 6 indicates the beater tub or trough. The tub or trough 6 differs from the usual beater tub or trough in that it possesses no midfeather, but consists of a continuous or endless ring-like trough 7 in which the raw material or stock to be pulped and the water for softening the same is circulated. Arranged within the trough 7 at one point, so as to be mounted between the inner and outer side walls thereof, is a primary beater roll 8, the transverse shaft 9 of which is journaled in suitably constructed and disposed bearing supports 10. Said primary beater roll 8 is driven from a suitable source of power and by suitable power transmission means (not shown) through a pulley 11 or other device which is fixed on its shaft 9. Extending longitudinally of and radially projecting from the cylindrical surface of said primary beater roll are a plurality of fly-bars. These fly-bars preferably comprise a series of toothed bars 12 alternated with straight-edged bars 13, as shown in Figure 4 of the drawings. Fixed in the floor of the trough 7, so as to be opposed to and beneath the primary beater roll 8 is a bed-plate 14 provided with a series of upstanding stationary bed-blades 15, or any other form of bed-plate may be provided. Extending upwardly and forwardly from the bed-plate 14, on the discharge side of the primary beater-roll 8, is the apron plate 16 of a forwardly and downwardly sloping back-fall 17, in the manner common to paper pulp beaters. The said primary beater roll 8 is set in a rela-

tively wide spaced off-set relation to the bed-plate 14 and its bed-blades 15, for purposes subsequently to be described.

Arranged within the trough 7, at a point 5 preferably diametrically opposite the position of said primary beater roll 8, is a secondary beater roll 18, which is mounted between the inner and outer side walls of said trough 7. Said secondary beater roll 10 18 is fixed on a transverse shaft 19 which is suitably journaled in bearing supports 20. Said secondary beater roll 18 is also driven from a suitable source of power by any convenient transmission means (not 15 shown) through a pulley 21 or other device which is fixed on its shaft 19. Extending longitudinally of and radially projecting from the cylindrical surface of said secondary beater roll are a plurality of fly-bars 22, preferably possessing straight edges, as shown in Figure 5 of the drawings. Fixed in the floor of the trough 7, so as to be opposed to and beneath said secondary beater roll 18 is a bed-plate 23 provided with a series of upstanding stationary bed-blades 24, or any other suitable 20 form of bed-plate may be provided. Extending upwardly and forwardly from said bed-plate 23, on the discharge side of said secondary beater roll 18, is the apron plate 25 of a forwardly and downwardly sloping back-fall 26, in the manner common to paper pulp beaters. Said secondary beater roll 18 is set in relatively close grinding or beating 30 relation to the bed-plate 23 and its bed-blades 24.

The arrangement and relation of the said primary and secondary beater rolls 8 and 18 and the shape and construction of the trough 7 is such that a substantially semi-circular trough-way A extends from the back-fall at the discharge side of the primary beater roll 8 to the receiving side of the secondary beater roll 18; and similarly 40 a substantially semi-circular trough-way B extends from the back-fall at the discharge side of the secondary beater roll 18 back to the receiving side of the primary beater roll 8, thus providing, what may be termed, a continuous "circular-run" trough or tub, in which the beater rolls are set at diametrically opposite points. Such novel shape and construction of trough or tub tends to permit a rapid and continuous circulation of 50 the material or stock, together with the softening water, from one beater roll to the other; the semi-circular trough-ways A and B providing a natural guiding sweep from one beater roll to the other, so that the fluid mass of stock and water does not loose head-way or momentum by reason of comparatively sharp and sudden changes of direction, and consequently not only is a more rapid circulation of the fluid mass attained, 60 but likelihood of masses of stock settling in

the bottom of the trough is avoided. To further aid in attaining a rapid circulation of the fluid mass of stock and water through the trough-ways A and B, the said trough-way A is provided with a forwardly and 70 downwardly inclined bottom 27 extending from the back-fall of the primary beater roll 8 to the secondary beater roll 18; and, in like manner, the said trough-way B is provided with a forwardly and downwardly 75 inclined bottom 28 extending from the back-fall of the secondary beater roll 18 to the primary beater roll 8.

Suitable cover members 29 are arranged over the primary beater roll 8 and its back-fall, and similarly cover members 30 are arranged over the secondary beater roll 18 and its back-fall.

The stock to be pulped may be introduced into the beater trough at the receiving side 85 of the primary beater roll 8 in any suitable manner and by any suitable means. Illustrative of one manner of delivering the stock, there is shown in the drawings a delivery chute 31 by means of which the stock 90 is conveyed into the trough.

As above stated, the primary beater roll 8 is spaced upwardly from the bed-plate 14 and its bed-blades 15, thus producing, what 95 may be characterized as, a relatively coarse setting of said of said primary beater roll 8. This coarse setting of the primary beater roll 8, together with the provision of the toothed fly-bars 12, permits an initial treatment of the stock, which tends to quickly 100 disintegrate the mass thereof, and thereupon discharge the same over the adjacent back-fall with a minimum tendency to clogging 105 at any point, while at the same time thoroughly distributing the initially disintegrated stock through the softening water in circulation around the trough. The initially disintegrated stock discharged from the primary beater roll 8 is carried by the 110 circulating water around the trough-way A, and between the secondary beater roll 18 and its cooperating bed-plate 23 with its bed-blades 24. As above stated, the secondary beater roll 18 is set relatively close to 115 the bed-plate 23 and its bed-blades 24 in, what may be characterized as, a relatively fine setting, and consequently as the initially 120 disintegrated stock passes between the secondary beater roll 18 and its bed-plate 23, the stock is more finely ground, and its fibres teased out and liberated, by the movement 125 of the fly-bars 22 of the former across the bed-blades 24 of the latter. The stock thus pulped is delivered over the back-fall which is adjacent to the secondary beater-roll 18, and is circulated through the trough-way B back to the primary beater roll 8; these operations being continued until the stock is 130 thoroughly and completely pulped. Owing 135 to the novel arrangement and construction

of trough or tub, as well as to the provision of the primary and secondary beater rolls, the operation of pulping the stock, especially in the case of comparatively tough stock, such as straw, is very rapidly and efficiently accomplished without congestion or clogging. The thoroughly pulped stock may be discharged from the tub or trough, through a discharge pipe 32 in the usual manner. If desired, the floor of the trough, adjacent to the beater roll 18, may be provided with a sump or basin 33, to catch and hold out of the fluid mass any heavy foreign substances or materials accidentally entering the beater with the raw stock.

It is quite possible to operate the novel construction of pulp beater which is the subject of this invention as a continuous self-discharging beater, by providing in connection with and in operative relation to the secondary beater roll 18, a discharge means such as shown and described in prior Letters Patent of the United States heretofore granted to me, and respectively numbered and dated, 1,277,628, of September 3rd, 1918; 1,277,629 of September 3rd, 1918; 1,277,630, of September 3rd, 1918; or 1,380,920, of June 7th, 1921.

In order to aid the movement or flow of stock over the back-falls of the respective beater rolls 8 and 18, and to prevent the stock from being carried backward over the latter, I have found it convenient to provide water showers, which are given a forward direction, and which tend to impel the stock over and down the back-fall to the trough-ways A and B. The said showers are provided by means of perforate water discharge pipes, which extend transversely above the back-falls, and comprise a rear discharge pipe 34 intermediate a beater-roll and the top of the adjacent back-fall, the shower or sprays from which are directed across the space intermediate the said beater roll and the apron plate of the adjacent back-fall so that when the stock is thrown up toward the top of the back-fall by the beater roll, it will be impelled forward by the shower of spray to fall upon the downwardly and forwardly sloping back-fall face, and will not tend to fall back and be carried rearwardly over the roll; one or more similar forward discharge pipes 34' are located above the downwardly and forwardly sloping back-fall face, so that the showers or sprays issuing therefrom are directed toward the latter, and thus tend to wash the stock forward and down the back-fall face into the communicating trough-way. The showers or sprays thus provided by the discharge pipes 34 and 34' tend to prevent collection or accumulation of partially beaten stock in and around the back-falls of the beater rolls, and thus eliminate tendencies to obstruction or clogging of the

path of circulation of the stock. Said discharge pipes 34 and 34' are connected with headers 35, and through the latter with water supply piping 36. If desired, each discharge pipe may be equipped with a 70 shut-off valve 37, so that the operation and functioning of the same may be individually controlled. The above described system of water shower pipes is of especial advantage when the pulp beater is employed for 75 pulping comparatively tough raw stock, such, for example, as straw.

From the above description it will be quite evident, by reason of the novel shape of the beater trough, together with the provision of the primary and secondary beater rolls, that a very rapid and substantially unimpeded circulation of the raw stock, with the softening and cleansing water, may be attained, whereby the said stock will be 80 more frequently delivered beneath the beater-rolls, and consequently more rapidly broken down or beaten out into the desired 85 pulpy consistency, and with the fibres thereof thoroughly separated and conditioned 90 for delivery to paper making machinery.

I am aware that some changes may be made in the general arrangements and combinations of the various devices and parts comprising this invention, as well as in the 95 details of the construction of the same, without departing from the scope thereof as described in the foregoing specification, and as defined in the appended claims. Hence, I do not limit this invention to the 100 exact arrangements and combinations of the devices and parts as set forth in the foregoing specification, nor do I confine myself to the exact details of the construction of 105 said parts as illustrated in the accompanying drawings.

I claim:—

1. A pulp beater, comprising a tub having a substantially annular troughway, a primary beater roll, a secondary beater roll, 110 said beater rolls occupying diametrically opposite positions within said troughway, a bed-plate beneath each roll, a back-fall at the discharge side of each roll, said primary beater roll being disposed in relatively 115 widely spaced relation to its cooperating bed-plate, said secondary beater roll being disposed in relatively closely spaced relation to its cooperating bed-plate, said primary beater roll having a plurality of toothed fly-bars, projecting radially from its surface, and said secondary beater roll having straight edged fly-bars projecting radially from its surface.

2. A pulp beater, comprising a tub having a substantially annular troughway, a primary beater roll, a secondary beater roll, 120 said beater rolls occupying diametrically opposite positions within said troughway, a bed-plate beneath each roll, a back-fall at 125

the discharge side of each roll, said primary beater roll being disposed in relatively widely spaced relation to its cooperating bed-plate, said secondary beater roll being disposed in relatively closely spaced relation to its cooperating bed-plate, the floor of said trough being inclined downwardly and forwardly from the back-fall of each beater roll to the receiving side of the opposite beater roll, said primary beater roll having a plurality of toothed fly-bars projecting radially from its surface, said secondary beater roll having straight edged fly-bars projecting radially from its surface.

3. A pulp beater, comprising an endless tub, a pair of beater rolls occupying diametrically opposite positions within said tub, a bed-plate beneath each roll, a back-fall at the discharge side of each roll, said tub being shaped to provide a substantially semi-circular troughway extending from the back-fall of each roll to the receiving side of the opposite roll, the floors of said troughways being inclined from the back-fall of each roll to the receiving side of the opposite roll, and transverse water shower discharge means above the back-fall of each roll.

4. A pulp beater, comprising an endless tub, a pair of beater rolls occupying diametrically opposite positions within said tub, a bed-plate beneath each roll, a back-fall at the discharge side of each roll, said tub being shaped to provide a substantially semi-circular troughway extending from the back-fall of each roll to the receiving side of the opposite roll, the floors of said troughways being inclined from the back-fall of each roll to the receiving side of the opposite roll, a transverse water shower discharge means intermediate each beater roll and the top of the adjacent back-fall adapted to direct a shower toward the latter, and additional water shower discharge means above said adjacent back-fall adapted to direct a shower downwardly and forwardly over the latter.

5. A pulp beater, comprising an endless tub, a primary beater roll, a secondary beater roll, said beater rolls occupying diametrically opposite positions within said tub, a bed-plate beneath each beater roll, a back-fall at the discharge side of each beater roll, said tub being shaped to provide a substantially semi-circular downwardly and forwardly inclined troughway extending from the back-fall of each beater roll to the receiving side of the opposite beater roll, said primary beater roll being disposed in relatively widely spaced relation to its cooperating bed-plate, said secondary beater roll being disposed in relatively closely spaced relation to its cooperating bed-plate, and transverse water shower discharge means above the back fall of each roll.

6. A pulp beater, comprising an endless tub, a primary beater roll, a secondary beater roll, said beater rolls occupying diametrically opposite positions within said tub, a bed-plate beneath each beater roll, a back-fall at the discharge side of each beater roll, said tub being shaped to provide a substantially semi-circular downwardly and forwardly inclined troughway extending from the back-fall of each beater roll to the receiving side of the opposite beater roll, said primary beater roll being disposed in relatively widely spaced relation to its cooperating bed-plate, said secondary beater roll being disposed in relatively closely spaced relation to its cooperating bed-plate, a transverse water shower discharge means intermediate each beater roll and the top of the adjacent back-fall adapted to direct a shower toward the latter, and additional water shower discharge means above said adjacent back-fall adapted to direct a shower downwardly and forwardly over the latter.

In testimony that I claim the invention set forth above I have hereunto set my hand this 27th day of March, 1925.

SIDNEY MITCHELL.
